UNITED STATES PATENT OFFICE

JOSEPH D. BASSON, OF BROOKLYN, NEW YORK

COMBINED SHUTTER AND VENTILATOR

Application filed June 24, 1930. Serial No. 463,467.

This invention relates to projecting machines in general and more especially to a combined shutter and ventilator.

Among the objects of the present invention it is aimed to provide a rotor constituting a combined shutter and ventilator which will intercept the light rays in the usual way during the movement of the film and at the same time effectively draw the heated air from the film.

It is still another object of the invention to provide an improved combination shutter and ventilator for intercepting the light rays in the usual way and at the same time draw the air from the film thus to prevent the over-heating of the film and direct such air outwardly away from the lamp so that a current of air will be established outwardly from the space between the film and the lamp and thus prevent not only the concentration of the heat on the film but in addition prevent the deflection of dust particles and the like from the film onto the lamp.

These and other features, capabilities and advantages of the invention will appear from the subjoined detail description of one specific embodiment thereof illustrated in the accompanying drawing in which

Figure 1 is an end elevation of the rotor attached to a projecting machine;

Fig. 2 is a section on the line 2—2 of Fig. 1; and

Fig. 3 is a plan of the rotor detached with the lower blades not shown.

In the embodiment illustrated, there is shown a housing 1 of a usual projecting machine through which a film 2 passes down from the reel housing 3 to the reel housing 4. The projecting machine in the housing 1 is equipped with a shaft 5 associated with the driving mechanism of the projecting machine.

On the side of the lamp housing 1 in which the light aperture is located, there are provided the arms 6 and 7. To the arm 6 a bracket 8 is secured, the ends of which are secured to the upper portion of a casing 9. The lower portion of the casing 9 is connected by the arm 10 to the arm 7. The casing 9, in the present instance, consists of two cir-

cular sections 11 and 12 having opposing flanges 13 and 14, illustrated in Fig. 1, which are secured to one another by any suitable means such as the screws 15 indicated in Fig. 2. The opposing plane walls 16 and 17 of the sections 11 and 12 are perforated to form a grille, as indicated in Fig. 2. The section 11 of the casing 9, as indicated, is the one secured to the bracket 8 and arm 10.

The sections 16 and 17 are provided with central openings 18 and 19. Through the opening 18 extends the stub shaft 20 of the rotor 21 which is secured to the shaft 5. The stub shaft 20, as indicated in Fig. 3, is split at 22 and provided with screws 23, 23, to frictionally clamp the stub shaft 20 onto the shaft 5. The stub shaft 20 extends from the hub 24 of the rotor 21 which is provided with two angular extensions 25 and 26. Each of the extensions 25 and 26 has two wing portions 27 and 28, as indicated in Fig. 3, which are preferably inclined to one another.

To the outer faces of the wing portions 27 and 28 of the extension 26, are secured the blade members 29 and 30 respectively. To the outer faces of the wing portions 27 and 28 of the extension 25 are provided the blade members 31 and 32 respectively. To the outer face of the hub 24, facing the section 17 of the casing 9, there are secured the plane blade members 33 and 34 respectively, see particularly Fig. 2. Preferably, the blades 29, 30 and 33 are stamped out of one piece, as indicated, in which case the blades 29 and 30 are connected to the blade 33 by the narrow strips 35 and 36 respectively, and similarly, the blades 31, 32 and 34 are stamped out of one piece, in which case the free outer edges of the blades 31 and 32 are connected to the outer edge of the blade 34 by the narrow strips 37 and 38 respectively.

As indicated in Fig. 2, the blades 29 and 30 register with the blade 33 and the blades 31 and 32 register with the blade 34. The blades 33 and 34 extend in a plane perpendicular to the axis of the hub 24 and would ordinarily constitute the usual shutter of the projecting machine and when rotated pass the openings 39 formed in the sections 16 and 17. These openings 39 register with one

another and with the light aperture of the projecting machine, not shown.

The blades 29, 30, and 31, 32, register with the blades 33 and 34 respectively, as aforesaid, and thus do not interfere with the usual action of the shutter formed by the blades 33 and 34. Due, however, to the fact that the blades 29, 30, and 31, 32, are inclined relative to the plane of the blades 33 and 34, as indicated in Figs. 1 and 3, they will, when rotated in the direction of the arrow 40 indicated in Fig. 2, act as a fan to draw the air from the film 2. If the blades 33 and 34 were not disposed adjacent to the blades 29, 30, and 31, 32, as indicated, the air so drawn from the film 2, carrying with it as is not unusual particles of dirt and shavings from the film, would direct the same toward the lamp, not shown.

If the lamp used consists of a carbon arc, such air currents directed toward the luminous portion would cause the same to flicker. If a reflector and/or a condenser is used with the lamp, the dirt particles directed toward the lamp would collect on the same and obviously affect its efficiency. If the lamp consisted of an electric bulb, such particles of dirt and shavings would quickly accumulate and collect on the glass bulb and affect its efficiency.

The blades 33 and 34, in the present instance, thus serve as a deflecting shield to cause the air and dirt particles drawn from the film to be directed outwardly with the centrifugal force of the rotor 21 and thus tend not only to draw the air from the film outwardly but also to draw the heated air from the lamp outwardly away from the film. Due to the fact that the free outer edges of the blades 29, 30 and 31, 32, are spaced from the outer edges of the blades 33 and 34, the resistance offered by this rotor 21 is considerably reduced, thereby reducing the load on the driving mechanism and the efficiency of the shutter and ventilator is not affected in any way.

It is obvious that various changes and modifications may be made to the details of construction without departing from the general spirit of the invention as set forth in the appended claims.

I claim:

1. A combined projecting machine shutter and ventilator having a hub, a plurality of inclined blades fixed on said hub and inclined in the same direction to a plane extending vertically to the axis of the hub, and a plurality of deflecting blades fixed on said hub to extend perpendicularly to the axis of the hub, in aggregate area corresponding substantially to the aggregate area of said inclined blades, and in registration with said inclined blades, said inclined blades drawing the air from the film of the projecting machine and said deflecting blades di-

recting it outwardly away from the lamp of the projecting machine.

2. The combination with a projecting machine having a film and a lamp, of a rotor operably disposed between said film and said lamp, said rotor having inclined blades inclined in the same direction to a plane extending perpendicularly to the axis of the rotor for drawing the air from the film and deflecting blades disposed perpendicularly to the axis of the rotor for deflecting the air so drawn outwardly away from the lamp, said blades being spaced from one another radially to intercept intermittently the beam of light in the usual way during the feeding interval of the film, the aggregate area of the inclined blades corresponding substantially to the aggregate area of the deflecting blades, and the inclined blades registering with the deflecting blades, said sets of blades being spaced coaxially with relation to each other.

3. A combined projecting machine shutter and ventilator having a hub, a pair of spaced blades perpendicular to the axis of said hub and mounted thereon, and a set of blades mounted on said hub and inclined in the same direction to the plane of said pair of blades, said set of inclined blades being aligned with said pair of blades, and the aggregate area of said perpendicular blades being substantially equal to the aggregate area of said inclined blades.

4. A combined projecting machine shutter and ventilator having a hub, a pair of blades spaced from one another extending perpendicular to the axis of said hub and mounted on said hub, and two pairs of inclined blades inclined in the same direction to said perpendicular blades and mounted on said hub with their outer free edges spaced from the outer free edges of said first pair of blades; each pair of inclined blades being in alignment with one blade of said first pair of blades, and the aggregate area of said perpendicular blades being substantially equal to the aggregate area of said inclined blades and being substantially equal to one half of the area of the circle described by said blades.

5. A combined projecting machine shutter and ventilator having a hub, two sets of blades mounted on said hub and spaced from one another, each set consisting of a blade perpendicular to the axis of said hub and two blades incline in the same direction to a plane perpendicular to the axis of the hub, the outer free edges of each set of blades being spaced from one another, and strips for connecting the outer free edges of the blades of each set to one another.

6. A combined projecting machine shutter and ventilator having a hub, two sets of blades mounted on said hub, each set consisting of a plane blade and two inclined blades, the plane blade being perpendicular

to the axis of the hub and the inclined blades being inclined to said plane blade, the outer free edges of each set of blades being spaced from one another, and a strip connecting the outer free edge of each inclined blade of each set to the plane blade of such set.

7. A combined projecting machine shutter and ventilator having a hub, a plurality of pairs of blades mounted on said hub and spaced from one another, each set of blades consisting of a plane blade and two inclined blades, the plane blades being perpendicular to the axis of the hub, the inclined blades being inclined to the plane blades, and strips for connecting the outer free edges of the inclined blades of each set to the plane blade of such set.

8. A combined projecting machine shutter and ventilator having a hub, a plurality of sets of blades, each set of blades being stamped out of a single sheet of metal and consisting of a plane blade and two inclined blades connected to one another, the plane blade being perpendicular to the axis of the hub and the inclined blades being inclined to said plane blade.
